UNITED STATES PATENT OFFICE.

WILLIAM F. NICODEMUS, OF JOHNSTOWN, PENNSYLVANIA, ASSIGNEE, BY MESNE
ASSIGNMENTS, TO LA COLLE GRADING MACHINE CO., INC., OF JOHNSTOWN,
PENNSYLVANIA.

EXCAVATING APPARATUS.

1,202,881.

Specification of Letters Patent. Patented Oct. 31, 1916.

Application filed August 9, 1911, Serial No. 643,157. Renewed December 5, 1914. Serial No. 875,721.

To all whom it may concern:

Be it known that I, WILLIAM F. NICODEMUS, a citizen of the United States, residing at Johnstown, in the county of Cambria and State of Pennsylvania, have invented a new and useful Excavating Apparatus, of which the following is a specification.

This invention relates to an excavating apparatus and consists in the novel construction and arrangement of its parts as herein-after described and claimed.

The object of the invention is to provide an apparatus of the character indicated which is of simple structure and which may be effectually used for quickly excavating material and conveying the same away from the excavation.

With this object in the view the apparatus includes a wheel mounted frame upon which is located a superstructure and within which is pivotally mounted a secondary frame. A beam is slidably mounted with relation to the said secondary frame and carries at one end a digging member. An engine is mounted upon the primary frame and means is provided for operatively connecting the said engine with the beam to move the same within the said secondary frame. A guiding chain is carried by the said beam and passes through a gripping device whereby the dropping movement of the digging element may be controlled. Conveyers are provided in conjunction with the apparatus and means are provided for operating the said conveyers from the engine.

In the accompanying drawings, Figure 1 is a top plan view of the excavating apparatus. Fig. 2 is a side elevation of the same. Fig. 3 is an end elevation of the same with parts broken away. Fig. 4 is a side elevation of a motion transmission device used in the apparatus. Fig. 5 is a side elevation of the digging elements forming a part of the apparatus.

The apparatus consists of a frame 1 which is mounted upon supporting wheels 2. An engine 3 is mounted upon the frame 1 and may be of any type or form. A superstructure 4 is mounted upon the frame 1 and a vertically disposed shaft 5 is journaled for rotation in the lower portion of the said superstructure 4. A secondary frame 6 is pivotally mounted upon the shaft 5 and is adapted to swing horizontally within the superstructure 4. A shaft 7 is journaled for

rotation in the secondary frame 6 and is provided with a beveled gear wheel 8 which meshes with a beveled gear wheel 9 fixed to the upper end of the shaft 5. A gear wheel 10 is fixed to the intermediate portion of the shaft 7 and meshes with gear teeth 11 carried by a beam 12. The said beam 12 is adapted to slide longitudinally through the secondary frame 6.

A roller 13 is journaled upon a table 14 which in turn is attached to the upper end of a shaft 15 journaled in the superstructure 4. The edge portions of the table 14 rest upon the rollers 16 journaled in the upper portion of the superstructure 4. The roller 13 is provided with a peripheral groove having link recesses 17 and a brake lever 18 is fulcrumed upon the table 14 and is provided with a shoe 18' adapted at times to frictionally engage the periphery of the roller 13.

The intermediate portion of a chain 19 is trained over the roller 13 and its links enter the recesses 17 whereby the chain cannot slip with relation to the roller. A beveled gear wheel 20 is fixed to the upper portion of the secondary frame 6 and the lower end of the shaft 15 and meshes with a beveled gear wheel 21 fixed to the end of a shaft 22 which is journaled upon the superstructure 4. A hand wheel 23 is fixed to the outer end of the shaft 22.

A disk 24 is fixed to the lower end of the shaft 5 and rollers 25 are journaled in the superstructure 4 and bear against the upper side of the disk 24 at diametrically opposed points.

A shaft 26 is journaled for rotation under the disk 24 and is square in transverse section as illustrated in Fig. 4 of the drawing. A friction roller 27 is slidably mounted upon the shaft 26 but is constrained to rotate in unison with the same. At times the upper portion of the periphery of the roller 27 is brought into frictional contact with the under surface of the disk 24 and serves as means for rotating the said disk in a manner which will be hereinafter explained. Each end of the shaft 26 is journaled in a pivoted bearing 28 and a lever 29 is fulcrumed upon the frame 1 and has its working end located under the free end portion of the bearing 28. A pulley 30 is fixed to the shaft 26 and a pulley 31 is fixed to the shaft of the engine 3. A belt 32 is trained around the pulleys 30 and 31 and is

adapted to transmit rotary movement from the engine to the shaft 26. A continuous cable 33 is trained around the pulleys 34 journaled upon the superstructure 4 and the shaft of one of the pulleys 34 is provided with a hand wheel 35 whereby the said pulley may be manually rotated. The cable 33 is provided at its lower run with upstanding lugs 36 which are located at the opposite sides of the roller 27.

A shaft 37 is journaled upon the frame 1 and is provided with a belt pulley 38. A pulley 39 is fixed to the shaft of the engine 3 and a belt 40 is trained around the pulleys 38 and 39 and is adapted to transmit rotary movement from the shaft of the engine 3 to the shaft 37. A stub shaft 41 is journaled upon the frame 1 at right angles to the shaft 37 and is provided with a beveled gear wheel 42 which meshes with a beveled gear wheel 43' fixed to the shaft 37. A trunk 44 is located beyond one end of the frame 1 and an endless belt 45 is arranged for movement along the said trunk. The belt 45 is trained around an operating shaft 46 which is journaled in the trunk 44 and a sprocket wheel 47 is mounted upon the said shaft 46. A shaft 48 is journaled upon the frame 1 and a sprocket wheel 49 is fixed thereto. A sprocket wheel 50 is also fixed to the shaft 48 and a sprocket chain 51 is trained around the sprocket wheels 50 and 47. An idle sprocket wheel 52 is journaled upon the frame 1 and a sprocket chain 53 is trained about the wheels 52, 49, and 54' carried by shaft 41. Therefore means is provided for transmitting movement from the engine 3 to the conveyer belt 45. The belt 45 is provided with cross strips 55 which project beyond the edges of the belt and operate under flanges at the side of the trunk 44 as shown in Fig. 2. The trunk 44 may also be provided with cross stays located between the upper and lower runs of the belt and the said stays may carry strips upon which the upper run of the belt may travel. A detachable elevator trunk 56 is applied to either end of the trunk 44 and is provided at its outer end with a roller 57 around which the outer portion of the belt 45 is trained. The trunk 44 is provided with a wheel 47 at each end and the chain 51 may be trained around either wheel 47 according to the direction it is desired to drive the belt 45.

An earth-engaging member is attached to one end of the beam 12 and consists of a curved bar 56' which carries a series of bits 57'. A spring arm 58 is attached at one end to the beam 12 and at its other end to the intermediate portion of the bar 56' and braces 59 are connected at their inner ends to the beam 12 and at their outer ends to the end portion of the bar 56'.

In using the apparatus the wheel 23 is

rotated and motion is thus transmitted through gears 21 and 20 to the shaft 15 and the secondary frame 6 which can thus be swung to the right or to the left, the beam 12 moving with it. Thus the bits 57' can be caused to engage the soil at one side or the other of the frame 1 or immediately in front of the end of the frame. By bearing down upon lever 18, shoe 18' is caused to contact with roller 13 to retard or entirely stop the rotation of the same. Thus the chain 19 which has its ends secured to the respective end portions of the beam 12 will be held against longitudinal movement and the bits 57' can be supported by the chain out of contact with the ground. The beam 12 is projected outwardly by depressing lever 29 which will result in bringing the rotating roller 27 in contact with the disk 24. Thus motion will be transmitted from said disk 24 through the gears controlled thereby to gear teeth or rack 11. The speed with which the beam 12 is moved forwardly depends upon the position of the roller 27 on the face of disk 24, this position being varied by the manipulation of the hand wheel 35. During the forward projection of the beam 12 the rotation of wheel 13 is retarded, thus allowing the chain 19 to move longitudinally at a sufficient speed to support the beam 12 in a substantially horizontal position. When the beam has been projected forwardly a desired distance the foot lever 29 is released, thus breaking the contact between the roller 27 and the disk 24 and by then releasing the wheel 13 so that it can rotate freely, the bit end of the beam 12 will swing downwardly with the result that the bits 57' will bite into the soil. The roller 27 is then shifted so that when it is brought against disk 24 by the manipulation of lever 29, the movement of the disk and of the beam 12 will be reversed with the result that the bits 57' will be drawn toward the conveyer 25 and this return movement of the bits can be controlled by retarding or releasing the wheel 13 and by raising or lowering the beam 12 and the frame 6. During the movement of the bits toward the trunk 44 and its conveyer, the roller 13 can be released so that the chain 19, which is secured to the two ends of the beam 12, will work freely over the roller. Thus as the bits drag over the ground and toward the conveyer they will draw the dirt so as to pile it in front of the conveyer, thereby allowing succeeding loads of dirt to be hauled up over this pile and onto the conveyer. By having the bits 57' connected to the beam 12 in the manner described, they will be presented at the proper angle to the ground during the dragging operation thus insuring effective action.

What is claimed is:—

1. Excavating apparatus including a longitudinally movable beam, a rack extending

therealong, means engaging the rack for moving the beam backwardly and forwardly, a roller supported for rotation above the beam; a flexible element secured 5 at its ends to the ends of the beam and extending over the roller, and means for controlling the rotation of the roller and the movement of said flexible connection, during the movement of the beam, and a soil engaging structure at one end of the beam.

2. Excavating apparatus including a tiltable beam, a rack extending longitudinally thereof, a pinion engaging the rack, means for actuating the pinion in either direction 15 to move the beam forwardly or rearwardly, said pinion constituting the fulcrum of the beam, a roller supported above said pinion and the beam, a chain secured at its ends to the respective ends of the beam and extending 20 over the roller, means for retarding or stopping the rotation of the roller during the manipulation of the beam thereby to shift the beam upwardly or downwardly or to maintain the beam at a predetermined 25 angle during the shifting of the beam by the pinion, and a soil engaging means at one end of the beam.

3. Excavating apparatus including a longitudinally movable beam, a rack extending therealong, means engaging the rack for 30 moving the beam backwardly and forwardly, a roller supported for rotation above the beam, a flexible element secured at its ends to the ends of the beam and extending over the roller, and means for controlling the rotation of the roller and the movement of said flexible connection, during the movement of the beam, and means 35 at one end of the beam for engaging and holding soil, said structure including braces inclined downwardly away from and fixedly 40 connected to the beam, an arcuate series of bits fixedly connected to the braces and inclined downwardly and inwardly relative to the beam, and a spring arm connecting said 45 series of bits to the beam.

In testimony that I claim the foregoing as my own, I have hereto affixed my signature in the presence of two witnesses.

WILLIAM F. NICODEMUS.
